SYLVANUS A. REED, OF NEW YORK, N. Y., ASSIGNOR TO THE REED PROPELLER CO.
INC., A CORPORATION OF NEW YORK

ATTACHMENT MEANS FOR AERONAUTICAL PROPELLERS

Application filed May 15, 1930. Serial No. 452,562.

My invention relates to aeronautical propellers, preferably of metal, and is an improvement on the mounting means described in my U. S. Patent #1,687,636, issued October 16, 1928.

In said issued patent I describe a metal aeronautical propeller made from a slab or plate or forging, of metal, preferably of strong aluminum alloy, and twisted continuously in one angular direction from tip to tip without any reversal of twist. The propeller mounting, in said patent, comprises means attached to the end of the engine drive shaft, said means having crotches supporting and retaining the propeller in its appropriate position.

My present improvement dispenses with a mounting means separate from and attached to the propeller drive shaft and instead thereof the drive shaft itself, or an extension thereof, is split longitudinally for a short distance from its outer end, thus forming a crotch or fork, the branches of which are preferably bent outwardly in opposite directions. The propeller is then placed in the fork or bifurcation and is secured to the bent branches at propeller radii adapted to favorable support of the engine torque and of the propeller thrust. I thus greatly simplify the attachment of the propeller to the engine shaft and effect a large saving in weight, complication and expense. I may also, if desired, add reinforcing means to prevent the shaft or crotch from splitting, distortion, or from other failure. Also, if desired, other reinforcing means may be added to insure the stability of the propeller in its position within the crotch.

In Figs. 1, 2, 3, 4, and 5, I have illustrated preferred forms of my improvements. Figs. 1, 2, and 3, show the same propeller in three different aspects. Fig. 1 is a side view, Fig. 2 a plan view, and Fig. 3 an end view of the central section cut off. Figs. 4 and 5 are enlarged views of certain details of construction.

Referring to Figs. 1, 2, and 3, in which the same numerals refer to the same features in all three views, 1 is a metal propeller, 2 and 3 are blades, $a-c$ is the central part, b is the

axial line, 4 is the engine drive shaft or drive shaft extension, as the case may be, 5, 6 are branches or bifurcations of 4, made by cutting a longitudinal slit in the shaft or shaft extension, thus dividing it into the two equal branches 5 and 6, and then bending 5 and 6 laterally in opposite directions, and then inwardly or outwardly to positions conforming each branch to the twist surface of the central part $a-c$ of 1.

8, 9 are bolt holes thru the branches 5, 6 and the adjacent parts of 1.

The propeller 1 is cut, carved or forged to appropriate shape, and is then twisted continuously in the same angular direction from tip to tip, as described in my U. S. patent aforesaid, so that the leading edge of blade 2 is carried over continuously to become the leading edge of blade 3, and the trailing edge of blade 2 is carried over continuously to become the trailing edge of blade 3. Also, so that at the axial line b , the angle of the plate (from which the propeller is formed) to the plane of rotation of the propeller is 90° , and the angles at various radii of the propeller measured from b , are those appropriate to the desired pitch.

Bolts or screws or rivets 10, 11 pass thru holes 8, 9 and secure the propeller to the branches 5, 6.

I may also reinforce the engine shaft or shaft extension 4 in the region of the bifurcation by a ring 12, Fig. 4, or by an enlargement 13, Fig. 5, or by any other and convenient means. Also, as shown in Fig. 4, I may reinforce the attachment of branches 5, 6 to blades 1, 2 by a central clamping means 14. Such clamping means preferably comprises a bolt 15 passing thru propeller 1 with washers 16 overlapping branches 5, 6, one on each side of the propeller, and firmly set up.

Preferably the branches 5, 6 are bent laterally in the plane of the slit and also in a plane at 90° from the plane of the slit as shown in Fig. 5, in which case the branches are appropriately flattened as by hammering or forging in order to afford a proper contact with the faces of the propeller, and to accommodate conveniently the bolt holes 8, 9.

The central part $a-c$, as illustrated, is

preferably of plate-like form with a cross-section wide in the axial plane and relatively narrow in a direction at right-angles thereto, altho I do not confine myself to a central cross-section thus relatively dimensioned. Moreover, it is not absolutely essential that the propeller per se be made of metal as it may conceivably be made of wood or other material.

10. What is claimed is:

1. In an attachment for aeronautical propellers, a drive shaft bifurcated at its outer end to receive in the crotch of the bifurcation that part of the propeller in the region of its rotation axis, said drive shaft having its branches bent in opposite directions, and each branch so attached to the propeller at equal radii from said axis as to give adequate resistance to the maximum thrust and torque to be experienced by the propeller in the service for which it is designed.
15. 2. In an attachment for aeronautical propellers, a drive shaft bifurcated at its outer end to receive in the crotch of the bifurcation that part of the propeller in the region of its rotation axis, said drive shaft having its branches bent in opposite directions and each branch having a sufficient cross-sectional area and being so attached to said propeller at equal radii from said axis as to give adequate resistance to the maximum thrust and torque to be experienced by the propeller in the service for which it is designed, as well as to insure constancy of pitch angle of the propeller blades.

20. 3. In an attachment means for a one-piece metal aeronautical propeller, a drive shaft bifurcated at its outer end to receive in the crotch of the bifurcation that part of the propeller in the region of its rotation axis, said drive shaft having its branches bent in opposite directions and each branch having a sufficient cross-sectional area and being so attached to said propeller at equal radii from said axis as to give adequate resistance to the maximum thrust and torque to be experienced by the propeller in the service for which it is designed, as well as to insure constancy of pitch angle of the propeller blades.

25. 4. A bifurcated drive shaft extension for an aeronautical engine, having its branches bent laterally in opposite directions and supporting in the crotch of the bifurcation an aeronautical propeller.

50. 5. A split drive shaft extension for an aeronautical engine having its integral branches bent laterally in opposite directions and supporting therebetween an aeronautical propeller.

55. 6. A bifurcated drive shaft extension for an aeronautical engine supporting in the crotch of the bifurcation an aeronautical propeller, and reinforcing means to fortify said crotch.

60. 7. A longitudinally split drive shaft ex-

70. tension for an aeronautical engine supporting in the crotch of the bifurcation a two-blade aeronautical propeller, the branches of the bifurcation engaging with and being fastened, one each, to and on opposite sides of one each of the propeller blades.

75. 8. A bifurcated drive shaft extension for an aeronautical propeller having its branches bent laterally in opposite directions and supporting in the crotch of the bifurcation an aeronautical propeller, means for fastening each said branch to said propeller at points laterally removed from the rotation axis of said propeller, and a clamping means for reinforcing said attachment means.

80. 9. In combination, an aeronautical propeller, and a longitudinally split drive shaft extension within the embrace of which said propeller is securely fastened.

85. In testimony whereof I hereunto affix my signature.
